United States Patent Office

Des. 207,754
Patented May 23, 1967

207,754

AIRPLANE

Rollo G. Smathers, Jr., Atlanta, Ga., assignor to Lockheed Aircraft Corporation, Burbank, Calif.

Filed Mar. 21, 1966, Ser. No. 1,555

Term of patent 14 years

(Cl. D71—1)

FIG. 1

FIG. 2

FIG. 3

FIG. 4

FIGURE 1 is a perspective view taken from the bottom front of an airplane embodying the present design; FIGURE 2 is a front elevation thereof;

FIGURE 3 is a side elevation thereof; and

FIGURE 4 is a bottom plan view thereof.

The essential features of the design reside in the portions shown in full lines on the drawings.

What is claimed is:

The ornamental design for an airplane, substantially as shown and described.
